UNITED STATES PATENT OFFICE.

CARLON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTHERN DAKOTA.

PROCESS FOR TREATING HYDROCARBONS.

Application filed January 12, 1920. Serial No. 350,868.

This invention relates to a process and apparatus for treating hydrocarbons, and refers more particularly to one adapted for the cracking of petroleum oils.

- 5 Among the salient objects of the invention are to provide a process whereby any substantial precipitation of carbon in the heated or cracking zone is prevented; to provide a process in which a plurality of 10 small, relatively solid streams of oil are passed through the cracking zone and then delivered to a vapor and expansion chamber located outside of the cracking zone; to provide a process in which the incoming oil 15 intermingles with a gas and undergoes a heat interchange with the outgoing vapors; to provide a process in which the incoming fresh oil mingles with the reflux condensate and is delivered to the cracking zone; to 20 provide a process in which the oil is passed through the cracking zone in a plurality of vertical streams; to provide a process in which the carbon containing residue is drawn out of the system and prevented from 25 returning to the cracking zone; to provide a process which can be operated as a continuous one; to provide a novel form of apparatus for carrying out the process, and in general to provide an improved process and 30 apparatus of the character referred to.

The single figure is a somewhat diagrammatic side elevation and vertical section of my improved apparatus.

Referring to the drawings, 1 designates 35 the furnace, in which is seated the still 2. This still 2 comprises a series of open-ended vertical pipes 3 connected at their lower ends to drum 4 and at their upper ends to drum 5. A gooseneck 6 leads from the upper end 40 of the drum 5 to upright pipe 7. The standard 7 delivers to an expansion chamber or vapor chamber 8, located outside of the fire zone. This chamber 8 is provided with 45 residue drawoff 9 controlled by throttle valve 10. Vapors pass out of the chamber 8 through upright 11 to a lower compartment 12 of a dephlegmator 13. The dephlegmator 13 has an intermediate compartment 14, an upper compartment 15, provided with the usual overflow pipes 16 and 17.

The vapors which are not condensed in the dephlegmator pass out through line 18 into water condenser 19 and thence through 50 pipe 20 to the receiver 21. The latter is

provided with liquid drawoff 22, controlled by valve 23, gas drawoff 24, controlled by valve 25. It is understood that the system is equipped with the usual pressure gauges, pyrometers and sight feeds. Fresh oil is delivered from any suitable source of supply by pump 26 and line 27 to the upper end of the dephlegmator. A valve 28 is interposed in the line 27. The reflux condensate in the dephlegmator and the heated fresh oil leave the lower part of the dephlegmator through line 29, which is connected to the drum 4 as shown.

The following illustrative run may be given. Starting with gas oil of 29° Baumé gravity from the Kansas field, it may be heated to a temperature of 750° F., at a pressure of 135 lbs. By passing it through the apparatus shown, substantially 35% to 40% of it may be converted into 58° Baumé 75 gravity gasoline. The oil may be fed continuously and the residuum drawn off continuously. The oil is so fed as to at all times keep the pipes 3 filled with oil.

It is to be understood, of course, that the pressure and temperature may vary as conditions require.

I claim as my invention:

1. A process of converting heavy into lighter hydrocarbons, consisting in passing the oil in relatively solid small streams through vertical tubes seated in a furnace, passing the oil to a vapor chamber, drawing off residue therefrom without recycling any part of said residue through the system, passing the vapors from said chamber to a dephlegmator where a portion of them are condensed, removing, condensing and collecting the portion uncondensed in said dephlegmator, and continuously feeding fresh oil and reflux condensate to the said vertical tubes, and preheating said fresh oil by the heat from the dephlegmator prior to the passage of said fresh oil to said vertical tubes.

2. A process of treating hydrocarbon oils consisting in continuously passing the oil in relatively small streams through vertical tubes seated in a furnace wherein the oil is subjected to a cracking temperature, in passing the oil from said tubes into an expansion chamber where a substantial vaporization occurs and from which no unvaporized oil is permitted to return to said streams, in passing the vapors issuing from said chamber

- ber through a dephlegmator, in continuously passing raw oil through said dephlegmator to come in physical contact with the vapors therein to preheat the raw oil and condense the heavier fractions of the vapors, in condensing the uncondensed vapors issuing from said dephlegmator and in collecting the resulting distillate, in passing reflux condensate and raw oil from said dephlegmator to the lower ends of said vertical tubes and in maintaining a super-atmospheric pressure on the system.
3. A process of treating hydrocarbon oil consisting in passing the oil in relatively small streams through vertical tubes seated in a furnace wherein the oil is heated to a cracking temperature, in passing the oil from said tubes into an enlarged expansion chamber wherein substantial vaporization

occurs, in continuously withdrawing residual oil from said expansion chamber without recirculating any part of said residual oil through the system, in passing vapors from said expansion chamber to a dephlegmator, in continuously passing raw oil through said dephlegmator to act as a dephlegmating medium for the vapors and to be preheated thereby, in passing such preheated raw oil and the reflux condensate resulting from the dephlegmation of the vapors to the lower ends of said tubes, in condensing the vapors issuing from said dephlegmator and collecting the resulting distillate and in maintaining a self generated vapor pressure on the oil undergoing conversion.
